UNITED STATES PATENT OFFICE.

ALFRED E. REMICK, OF PROVIDENCE, RHODE ISLAND.

EXPLOSIVE-GAS ENGINE.

No. 902,450.

Specification of Letters Patent. Patented Oct. 27, 1908.

Application filed March 22, 1907. Serial No. 363,861.

To all whom it may concern:

Be it known that I, ALFRED E. REMICK, a citizen of the United States of America, residing at Providence, in the county of Providence and State of Rhode Island, have invented new and useful Improvements in Explosive-Gas Engines, of which the following is a specification.

This invention relates to explosive gas engines, and one of the principal objects of the same is to provide an oscillatory piston engine of simple construction which will operate efficiently as a portable motor or as a stationary engine.

Another object of the invention is to simplify the construction of engines of this character, render them more compact and to provide means whereby all the parts are readily accessible for repairs and renewals.

Still another object of the invention is to provide simple and efficient means for lubricating the piston and the inner wall of the cylinder.

These and other objects can be attained by means of the construction illustrated in the accompanying drawing, in which:

Figure 1 is a side elevation of a portable oscillating piston gas engine made in accordance with my invention. Fig. 2 is a similar view looking at the opposite side or end of the cylinder, parts being omitted to better illustrate the valve operating mechanism. Fig. 3 is a side elevation looking into the cylinder, one of the cylinder heads being removed. Fig. 4 is an elevation and partial section of the engine. Fig. 5 is a side elevation of one of the valve operating levers. Fig. 6 is a similar view taken at right angles to Fig. 5. Fig. 7 is a detail view showing the relative arrangement of the two valve operating levers. Fig. 8 is a side elevation of the engine arranged as a stationary engine.

Referring to the drawings for a more particular description of my invention, the numeral 1 designates the cylinder, 2 is one of the cylinder heads and 3 is the other cylinder head, said heads being secured to the cylinder by means of bolts 4, and the cylinder being hollow to provide a water jacket or air space 5 provided with a screw cap 6 for filling the chamber 5 with water or other cooling medium.

The cylinder 1 is mounted upon a suitable use 1². Secured to the inner wall of the cylinder 1 at diametrically opposite points

are the V-shaped abutments 7, 8, said abutments having a central partition 9, and inclined side walls, as shown more particularly in Fig. 3. An oscillatory piston comprising a tubular sleeve 10 is mounted to oscillate between the cylinder heads 2 and 3, and is provided with suitable packing 11^a to form a tight joint in said cylinder heads. Connected to the sleeve 10 are the oppositely disposed pistons 11, 12, said pistons being provided with suitable packing 13, and oil ducts 14 extending through the pistons 11 and 12 and communicating with the bore of the sleeve 10, said bore forming an oil chamber 15. A suitable oil cup 16 is mounted on the sleeve 10 and communicates with the chamber 15 for feeding oil thereto. Oil ducts 17 extend across the ends of the pistons 11 and 12 to carry oil from the ducts 14 to the packing. The sleeve 10 is covered at one end by a suitable cap or head 18, and at the opposite end is provided with a cap carrying a lever 19 which is slotted at 20 for the attachment of a connecting rod 21, the lower end of which is pivotally connected at 22 to a crank 23 mounted on a shaft 24 carrying a pinion 25 which engages a gear wheel 26 mounted on a shaft 27. The shafts 24 and 27 are journaled in a bracket 28 formed on or secured to the base 1^a. A fly wheel 29 is mounted on the shaft 24. In the walls of the abutments 7 and 8 flaring valve seats 30, 31, 32, and 33 are provided and similar shaped valve heads 34 provided with valve stems 35 are operated to open and close by means of crank levers 36 pivoted at 37 in the cylinder head 3 and connected to the crank levers 36. On the outer side of the cylinder head 3 are links 38. For operating the valves through the links 38 bars or links 39 are provided, said bars or links, as shown in Fig. 5, being provided with lugs 40 and 41 designed to engage the links 38 and to move them in position to open the valves 34. Springs 42 are connected at one end to the links 38 and at their opposite ends to the bars or links 39. The bars or links 39 are provided with inwardly extending arms 43 carrying rollers 44 at their ends. On the shaft 27 a pair of cams 45 are fixed, said cams being adapted to engage the rollers 44 on the arms 43 to alternately lift and depress the bars 39 for opening and closing the ports or valve seats 30, 31, 32, 33 in the abutments. The abutments 7 and 8 are provided with

110

packing 46 to form a gas tight joint between said abutments and the outer surface of the sleeve 10.

Exhaust ports 47 and 48 are provided in the head 3 near the upper and lower portions thereof, said exhaust ports opening into the cylinder between the walls of the abutments. Intake ports 47^a and 48^a are provided in the cylinder head 2, said intake ports each having a spring seated check valve 47^b, as shown more particularly in Fig. 4. Sparking plugs of any suitable construction are secured in the openings 49 in the cylinder head 2.

The operation of my invention may be briefly described as follows: Gas is taken in through the intake opening 47^a, and is ignited between the valve 30 and the piston 11 which forces the piston 11 downward toward the valve 34 and the piston 12 upward toward the valve 31. This movement of the piston draws in a charge of gas through intake valve 48^a which serves to compress the charge taken in through intake opening 47^a, this charge being ignited as piston 12 is moving downward. This movement of the piston opens exhaust valve 30 letting out the spent gases and taking in a charge through intake valve 48^a, and so on alternately during the operation of the engine.

From the foregoing it will be obvious that my invention is of simple construction; is compact; ready access may be had to all the

parts, and the engine may be used either as a portable or a stationary engine.

Having thus described the invention, what I claim is:

1. In a gas engine, a cylinder, heads fitted to said cylinder and provided with central openings, V-shaped abutments within said cylinder, a sleeve mounted in said heads, pistons carried by said sleeve, valves in the walls of the abutments, a pair of bars connected together and provided with lugs, links connected to said valves and to said bars, and cams for operating said bars. 45

2. In a gas engine, the combination of a cylinder, hollow V-shaped abutments therein having inclined walls, a sleeve mounted to oscillate in the cylinder heads, pistons carried by the sleeve, the walls of the abutments being provided with inlet and outlet ports, valves for opening and closing said inlet and outlet ports, links connected to said valves, bars for operating said links, said bars having lugs to engage said links, a shaft, 50 55 cams on said shaft for lifting said bars, and springs connected to said links and bars for returning said valves after each operation.

In testimony whereof, I affix my signature in presence of two witnesses.

ALFRED E. REMICK.
